(57) **CLAIM**

The ornamental design for a shower system, as shown and described.

DESCRIPTION

FIG. 1 is a front perspective view of a shower system, showing the new design;

FIG. 2 is a front view of the shower system;

FIG. 3 is a rear view of the shower system;

FIG. 4 is a side view of the shower system;

FIG. 5 is another side view of the shower system;

FIG. 6 is a top view of the shower system;

FIG. 7 is a bottom view of the shower system;

FIG. 8 is a detailed view of portions of the shower system;

FIG. 9 is a detailed view of portions of the shower system;

FIG. 10 is a detailed view of a portion of the shower system;

FIG. 11 is a detailed portion of the shower system shown in FIG. 9;

FIG. 12 is a detailed portion of the shower system shown in FIG. 10; and,

FIG. 13 is a detailed portion of the shower system shown in FIG. 8.

The broken lines showing various elements of the shower system are included for the purpose of illustrating non-claimed subject matter and form no part of the claimed design.
